MORRIS S. WRIGHT, OF WORCESTER, MASSACHUSETTS, ASSIGNOR TO M. S. WRIGHT COMPANY, OF WORCESTER, MASSACHUSETTS, A CORPORATION OF MASSACHUSETTS.

APPARATUS FOR CLEANING CARPETS AND THE LIKE.

1,109,497.

Specification of Letters Patent.

Patented Sept. 1, 1914.

Continuation of application Serial No. 630,726, filed June 1, 1911. This application filed May 29, 1914.
Serial No. 841,737

To all whom it may concern:

Be it known that I, MORRIS S. WRIGHT, a citizen of the United States, residing at Worcester, in the county of Worcester and 5 State of Massachusetts, have invented certain new and useful Improvements in Apparatus for Cleaning Carpets and the like, of which the following is a specification, reference being had therein to the accompanying 1 drawing.

This invention relates to an improved apparatus for cleaning carpets and dust laden surfaces, and more particularly to an apparatus of this character wherein is employed 1 a dust receiving chamber and vacuum creating means in operative association therewith for drawing dust, dirt, etc., into said chamber, by suction.

A primary object of the invention is to 20 provide a novel apparatus of the character described, portable in character, easily manipulated, efficient in operation, and strong and durable in use.

A further object of the invention is to 25 provide an apparatus in which the parts thereof are closely assembled, and combined, thereby taking up a minimum amount of space, and rendering the device especially applicable for operation in confined places, 30 such as beneath a bed or other furniture.

Also the improvements embody a novel 35 construction and arrangement of vacuum creating means, and operating mechanism for the latter, actuated by the supporting 40 wheels, at the rear end of the apparatus.

It is also contemplated by the invention 45 to provide a removable dust inlet head or nozzle part of the dust receiving or vacuum chamber, and novel means of connection for 50 the same.

Other improvements and novel details in 55 the construction and arrangement of the various parts of the apparatus will be brought out more in detail in the description 45 to follow, which, for a clear understanding of the invention, should be considered in connection with the accompanying drawings, forming a part hereof, and wherein is disclosed, for the purpose of illustration, convenient and satisfactory embodiments of the invention. It is to be noted, in this connection, that minor changes in 60 the construction and arrangement of the

parts may be made without departing from the spirit of the invention or the principle 55 of operation of the various parts.

In the drawings:—Figure 1 is a longitudinal section of the machine with one form of dust inlet head applied thereto; Fig. 2 is a transverse section of the machine; Fig. 3 60 is a longitudinal section of the same; Fig. 4 is a front end elevation of the dust inlet head in position on the machine, and Fig. 5 is a vertical section of the apparatus.

Referring now more particularly to the 65 drawings, wherein like reference characters designate corresponding parts throughout the several views thereof, 1 is the bottom wall of a casing, 2 the top wall thereof, 3 an end wall, and 4 a transversely extending 70 partition dividing the casing into what may be called a dust receiving or vacuum chamber 5, and a wheel chamber 6. The top wall 2 of said casing is provided with one or more openings 7 adjacent the partition wall 4 at the rear end of the dust receiving chamber, there being one of said openings for each of the vacuum creating means, conveniently pneumatics or pumps about to be described. The said pumps each comprise 80 an elongated bottom wall 8, having an opening 9 communicating with the openings 7 of the vacuum chamber, and said bottom wall 8 rests upon the top wall 2 of the casing and is secured thereto in any desired 85 manner. The said bottom wall of the pump is preferably of a length to overlie both the vacuum chamber and wheel chamber.

10 is a movable wall for the pump, the same being hingedly connected in any desired manner, at 11, to the forward end of the stationary bottom wall 8. The movable wall 10 is otherwise united to the bottom wall 8 through the medium of the flexible side walls 12 and end wall 13.

The opening 7 is valve controlled, a valve 14 of any desired construction, being provided, but conveniently being pivoted at 14^a to the top wall 2 of the casing and free to swing at its opposite end. The valves 14 are preferably reinforced by a relative rigid backing, such as wood, 14^b, having a conical opening 14^c overlying the pivot pin, whereby to permit ready swinging movement of the valve and an overhang 14^d 105 tends to hold the valve in position.

The movable wall 10 of the pumps is provided with an opening 15 leading to the outside, and positioned over said opening is a valve 16, which latter conveniently takes the form of a flexible member secured at one end as by screws 17 to said wall 10, and spring held to its seat as by a spring or spring members 18 secured at one end to said wall 10 and at their opposite end to the free end of said member 16. A guide 19 may be provided to overlie the valve.

Suitable means are provided for limiting the inward movement of the movable wall 10, the same preferably including what may be termed a stop pin 20 secured to the top 2 of the casing and having an offset head 20^a adapted to engage within a recess 20^b in the movable top 10 when the latter is in lowered position. By providing the recess, the opposite walls 8 and 10 of the pump may assume positions close to one another, while at the same time direct contact is prevented.

For the purpose of illustration two pumps or pneumatics are shown, the same being separated from one another a sufficient distance for the operating connection to be presently referred to.

Suitable wheels 21 are provided which are preferably solid as shown, and have friction surfaces 22, which may be formed by providing a corrugated rubber tread for said wheels.

23 are shafts one for each wheel, the same being mounted in bearings 23^a secured to the casing, and the inner terminals of said shafts passing through apertures in the wheels 21. The wheels are conveniently secured to their respective shafts as by a pin 24 which passes through an elongated opening 25 in the wheel and through an opening extending transversely through the shaft 23.

The pumps are preferably actuated by suitable operative connections with the traction wheels 21, as follows:—26 is a pitman rod, there being one for each pump and secured at their upper ends to the sides of the rear end of the movable wall 10 of the pump. The wheels are provided with a transverse opening 28 through which passes a supporting bracket, or what may be termed a stub shaft 29, which latter is secured to the wheel as by providing an opening 30 which fits over the pin 24 before referred to. The rods 26 are loosely sleeved at their lower ends upon said stub shafts 29 and at their upper ends upon pins 27 projecting from the walls 10. The rods 26 are connected one to the other at their lower ends by a link rod 31 sleeved upon projecting ends 31^a of the stub shafts 29, with the result that while the movable wall of one of the pumps is elevated the movable wall of the opposite pump is lowered. By the particular construction and arrangement of bellows and operating connections at the sides thereof, a larger and

more efficient bellows, and more compact machine is made possible.

Since the wheels 21 are adjacent the adjoining or inner edges of the pumps, the apparatus is made compact, and at the same time the close association of said wheels constitutes them in effect a single bearing at the rear of the apparatus, substantially midway of its sides. This constitutes an important feature of the invention in that it renders the device applicable to floors or carpets which are uneven, the bearing provided by said wheels permitting the nozzle, to be described, at the forward end of the machine, to lie close to the floor from end to end, thereby resulting in greater efficiency than would be the case were the nozzle tilted by side wheels at the rear of the apparatus running over uneven surfaces.

The apparatus is portable in character, and movement is conveniently imparted by what may be called a push handle 34 having a bifurcated lower end, the opposite arms 35 of which are pivotally connected as by bolts 36 with the side walls of the casing. Means are provided for normally holding the said handle in an elevated position, which said means includes a bracket arm or rod 37 rotatably mounted adjacent the opposite ends in suitable bearings 38 secured to a removable cover adapted to inclose the pumps. The said rod has offset terminals 39 which in the elevated position of said bracket constitute supporting rests engaging the arms 35 of the handle. As stated, this rod 37 is rotatably mounted, whereby the arms may be lowered as desired, when the apparatus is not in use, or when it is desired to position the handle below the normal upright position, thereby rendering the apparatus capable of operating over covered surfaces, such as the floor beneath a bed or other article of furniture. The connection between the rod 37 and the bearing 38 is such as to frictionally hold the arms in upper position and a suitable stop 40 may be provided for limiting the downward movement of the arms 39. When said arms are in elevated position so as to hold the handle in its raised position, said arms constitute an effective and substantial support for the handle during the pushing of the machine by the operator, and at the same time should it be desired to elevate the forward end of the machine, so as to go over the edge of a carpet, a rug or the like, by imparting downward pressure on the handle which will be resisted by the arms 39, the forward end of the apparatus may be raised.

The vacuum chamber 5 has an opening at its forward end, and positioned in said chamber is a removable dust receiving and filtering bag 43.

The dust receiving inlet head or nozzle member may take various forms, one of

which is described, for the purpose of illustration, and being preferably removable as occasion demands. In the form of head illustrated, it will be observed that the same is of a size and shape to fit over the front end of the casing and has projecting pins or dowels 44 adapted to fit within recesses in a collar or wall 43^a constituting a frame surrounding the open mouth at the front end of said bag 43 and secured to the latter in any desired manner. A washer or diaphragm 43^b overlies the inner surface of the open end of the bag 43 and is outwardly extended at its edge 43^c whereby to overlie the edge of the bag and the edge of the bag frame 43^a as well as the edge of the front end of the casing, as more particularly illustrated in Fig. 1. It will be appreciated that the washer or diaphragm constitutes a protecting medium for the edge of the bag at its open end, and also constitutes a packing between the frame of the bag and the inner surface of the nozzle member 45. The washer or diaphragm further provides a packing between the end of the casing and the inner surface of the nozzle member 45. The dust receiving or nozzle head part is given the numeral 45. One or more bow spring members 46 are secured at their upper ends as at 46^a to the collar or wall 43^a, the body part of the springs being adapted to yieldably engage projections 47 on the sides of the casing, the opposite ends of said spring being free as shown. Arranged in a recess in the forward wall of the head adjacent the bottom thereof is a suitable buffer, conveniently of felt 48, which constitutes the foremost part of the apparatus, whereby furniture and the like will be protected. The body part of the head 45 is provided with an inlet opening 49 communicating with the open end of the casing, thereby constituting a passageway to the interior of the bag 43. Secured adjacent the upper end of said head 45, as by screws 50, are one or more bow spring members 51, the spring members being bent outwardly at their lower ends 51^a to suitably engage over the front surface of the head 45. The spring members are also provided intermediate their ends with a bent part or recess 51^b constituting a receiving pocket for a locking member carried by the casing. This locking member conveniently takes the form of a U-shaped bail, the opposite arms 52 of which are pivotally mounted on the sides of the casing at 52^a and a connecting arm 53 being adapted, when in lowered or locking position, to engage in the pockets or receiving recesses 51^b of the spring members. A suitable stop 54 may be provided for limiting the lowering movement of the bail.

From the construction described, it will be observed that the nozzle or head is readily assembled and removed simply by

rocking the bracket member on its pivots 52^a, swinging the same upwardly to release the head and downwardly to lock the latter in position. When the nozzle member is in position, the packing interposed between the nozzle member and end of the casing will be compressed, and said packing is of a length to overlie the front edge of the casing, whereby, when the nozzle member is in position, the packing will be compressed and maintain an air tight joint between these parts. The novel means for supporting the nozzle member in position is an important characteristic of the invention. It is necessary that the nozzle member be removed, and replaced, repeatedly for discharging the dust, and by the employment of the spring fastening means, this replacement may be readily accomplished and at all times ensure a uniform and tight joint between the nozzle member and casing.

The nozzle member preferably has a reinforced mouth piece A, in the form of a cap, frictionally held in place, whereby it may be removed and replaced, as desired. The cap is preferably constructed of steel and may have a nickel plated face. The cover for the casing is preferably formed of sheets of veneer, the top part B being bent at opposite ends to form a front B', and back B^a, and connected to the sides B^b. This makes a light and cheaply constructed cover, and one which is durable as well as pleasing in appearance.

In operation, the operator grasps the handle 43, and imparts back and forth movement to the apparatus, over the surface to be cleaned, and the double acting bellows, by reason of their connection with the drive wheels, maintain a continuous vacuum in the dust chamber. The dust laden air passing through the nozzle member into the dust chamber is filtered by the bag positioned within said chamber, and the filtered air finds an outlet into the pump, through the opening 7 and to the outside through the opening 15. Since the opening 7 is positioned at the rear of the bag, the bag will not be drawn up into the opening 7, due to the suction, thus, if desired, doing away with the necessity of a screen or the like for preventing the bag finding a seat in said opening 7. However, a screen 70 may be employed, to overlie said opening 7, since without such screen should the filtering bag be accidentally left out of the apparatus, and the pumps operated, the pumps would be flooded with dust.

Various matters shown and described in this application, and not claimed herein, are reserved for claiming in co-pending applications, or divisional applications to be subsequently filed.

I claim:

1. In a device of the character described,

- the combination of a box-like casing having a division wall intermediate its ends and an open end chamber, a nozzle member at the forward end of the casing constituting a closure for the open end of the chamber, suction bellows mounted upon the top of the casing and extending from adjacent the forward end to a point adjacent the rear end thereof beyond the said partition, said bellows communicating with the chamber, traction driving means secured on the casing at the rear of the partition beneath the rear ends of the bellows, and pitman connections from the driving means to the sides of the bellows, substantially as described.
2. In a device of the character described, the combination with a casing having a vacuum chamber therein and a removable nozzle member at the front of the vacuum chamber, of suction means comprising bellows mounted on the top of the casing, said bellows extending from a point adjacent the front to a point adjacent the rear of the casing, traction driving means located beneath the rear end of the bellows, and pitman connections between the bellows and the driving means and located to operate at the sides of the bellows.
3. In a device of the character described, the combination with a casing having a vacuum chamber therein and means for creating a vacuum in the chamber, of a removable nozzle member at the end of the chamber, means for securing the nozzle member on the chamber comprising a swinging member, a spring coacting with the swinging member to normally hold the nozzle member uniformly in tight contact with the walls of the opening in the casing, and a filtering bag having an open mouth with a surrounding frame, and means for holding the frame in air tight contact with the nozzle member.
4. In a device of the character described, the combination with a casing having a vacuum chamber and means for creating a vacuum in the chamber, of a nozzle member detachably positioned at the end of the vacuum chamber and carrying a curved spring member, a bail secured to the casing and projecting across the front of the nozzle member into engagement with the spring member, and a filtering bag in the vacuum chamber having a frame member at its forward open end, and means for holding the frame member in position within the vacuum chamber.
5. In a device of the character described, the combination with a casing having a vacuum chamber therein and means for creating a vacuum in the chamber, of a removable nozzle member at the end of the chamber having a plurality of bow shaped springs thereon, a bail member secured to the casing and having its free outer end extending crosswise of the frame and adapted to engage the bow shaped springs, and a filtering bag associated with the nozzle member and located within the chamber.
6. In a device of the character described, the combination with a casing having a vacuum chamber therein, with an open end, and means for creating a vacuum in the chamber, of a nozzle member fashioned to fit over the open end to form a closure therefor, a filter bag located within the chamber and having an open end adjacent the nozzle member, said open end being provided with a surrounding frame, and means for yieldingly pressing the said bag frame against the nozzle member, and a yielding means for pressing the nozzle member uniformly against the casing and for retaining the nozzle member in its position.
7. In a device of the character described, the combination with a casing having an open ended vacuum chamber therein, and means for creating a vacuum in the chamber, of a nozzle member for closing the open end of the chamber, a U-shaped bail secured on the casing and extending across the nozzle, and means on the face of the nozzle member with which the bail engages for securing the nozzle member in position on the casing, and a filter bag within the casing having an open end supported adjacent the nozzle member.
8. In a device of the character described, the combination with a casing having an open ended vacuum chamber, means for creating a vacuum in the chamber, of a nozzle member for closing said open end, means for detachably securing the nozzle member in position, an open end filter bag within the chamber having a surrounding frame at its open end, and a washer on the frame having its outer edges extending between the nozzle member and the edges of the frame and constituting a packing between the frame and nozzle member and also a protecting covering for the edges of the filter bag.
9. In a device of the character described, the combination with a casing having an open ended vacuum chamber, means for creating a vacuum in the chamber, of a nozzle member for closing said open end, means for detachably securing the nozzle member in position, an open end filter bag within the chamber having a surrounding frame at its open end, and a washer on the frame having its outer edges extending outwardly and overlying the edges of the front end of the casing, the said washer constituting a packing between the frame of the bag and the nozzle member and between the edges of the wall of the casing and the nozzle member, and forming a protecting covering for the edges of the filter bag.
10. In a device of the character described, a box-like casing forming a vacuum cham-

ber, vacuum creating means, said casing having an open side, a removable nozzle member having a dust inlet opening and constituting a closure for said open side of the casing, and means for holding the nozzle member in position on the casing by constant spring pressure.

11. In an apparatus of the character described, a casing having an opening at one end, vacuum creating means, a removable nozzle member to engage over said opening and constituting a closure therefor, the said nozzle member having an opening in its lower edge, means for supporting said nozzle member in position, said means including an elongated bow spring arm connected at one end to the outer surface of the nozzle member adjacent its upper edge and free at its opposite end to engage said outer surface, and a movable locking device carried by the casing and engaging said arm.

12. In an apparatus of the character described, a casing having an opening at one end, vacuum creating means, a removable nozzle member to engage over said opening and constituting a closure for said opening, the nozzle member having an opening in its lower edge, means for supporting said nozzle

member in position, said means including an elongated bow spring arm connected at one end to the outer surface of the nozzle member adjacent its upper end and free at its opposite end, and having a receiving recess intermediate its ends, and a substantially U-shaped bail pivoted to the sides of the casing and adapted to engage the recess portion of said arm and properly position the nozzle relative to the surface and retain the same in closed relation with the casing.

13. In a device of the character described the combination with a casing having an open ended vacuum chamber, and means for creating a vacuum in the chamber, of a nozzle member for closing the open end of the chamber, a substantially U-shaped nozzle securing bail pivoted at the sides of the casing and adapted to swing into a position overlying the front of the nozzle member, and bail engaging means on the nozzle member.

In testimony whereof, I hereunto affix my signature in the presence of two witnesses.

MORRIS S. WRIGHT.
